UNITED STATES PATENT OFFICE.

ARCHIBALD McCALLUM, OF HALIFAX, ENGLAND, ASSIGNOR TO JOSEPH WILD & CO., OF NEW YORK CITY.

DESIGN FOR A CARPET-PATTERN.

Specification forming part of Design No. 5,417, dated December 12, 1871.

To all whom it may concern:

Be it known that I, ARCHIBALD McCALLUM, of Halifax, in the county of York, England, have invented a new and original Design for a Carpet, of which the following is a specification:

In the drawing, k l m represent the series of figures arranged with respect to each other as exhibited thereon.

The nature of my design is fully represented in the accompanying photographic illustration, to which reference is made.

I claim as my invention—
The design for a carpet, as shown.

ARCHIBALD McCALLUM.
